DESIGN FOR A RAIL FOR A BABY CARRIAGE OR THE LIKE

Samuel Kroll and Nathan J. Kroll, Chicago, Ill.

Application January 4, 1934, Serial No. 50,309

Term of patent 7 years

To all whom it may concern:

Be it known that we, SAMUEL KROLL and NATHAN J. KROLL, citizens of the United States, residing at Chicago, in the county of Cook and State of Illinois, have invented a new, original, and ornamental Design for a Rail for a Baby Carriage or the like, of which the following is a specification, reference being had to the accompanying drawing forming part thereof, and in which:

Fig. 1 is a perspective view of a rail for a baby carriage showing the new design; and

Fig. 2 is a sectional detail view of the same taken substantially on line 2—2 of Fig. 1 and shown to a somewhat enlarged scale.

We claim:

The ornamental design for a rail for a baby carriage or the like as shown.

SAMUEL KROLL.
